(57) **CLAIM**

I claim the ornamental design for a shotgun shell dispenser, as shown and described.

DESCRIPTION

FIG. 1 is a left side top isometric view of a shotgun shell dispenser showing a shell follower in a first position when a single shotgun shell is in the shotgun shell dispenser;

FIG. 2 is a right side bottom isometric view of the shotgun shell dispenser of FIG. 1 showing the shell follower in a second position when no shotgun shells are in the shotgun shell dispenser;

FIG. 3 is a left side view of the shotgun shell dispenser of FIG. 1 showing the shell follower in the second position when no shotgun shells are in the shotgun shell dispenser;

FIG. 4 is a front view of the shotgun shell dispenser of FIG. 1 showing the shell follower in the second position when no shotgun shells are in the shotgun shell dispenser;

FIG. 5 is a right side view of the shotgun shell dispenser of FIG. 1 showing the shell follower in the second position when no shotgun shells are in the shotgun shell dispenser;

FIG. 6 is a back view of the shotgun shell dispenser of FIG. 1;

FIG. 7 is a top view of the shotgun shell dispenser of FIG. 1 showing the shell follower in the second position when no shotgun shells are in the shotgun shell dispenser;

FIG. 8 is a bottom view of the shotgun shell dispenser of FIG. 1; and,

FIG. 9 is a left side isometric view of the shotgun shell dispenser of FIG. 1 with the belt loop removed and showing the shell follower in the first position when a single shotgun shell is in the shotgun shell dispenser.

In FIGS. 1-9, the broken lines indicating environmental features form no part of the claimed design.
